RAY P. PERRY, OF UPPER MONTCLAIR, NEW JERSEY, AND JOHN M. JACK, OF PEORIA, ILLINOIS, ASSIGNORS TO THE BARRETT COMPANY, A CORPORATION OF WEST VIRGINIA.

PROCESS OF AND APPARATUS FOR TREATING FELTS AND THE LIKE.

1,293,185.

Specification of Letters Patent.

Patented Feb. 4, 1919.

Application filed September 29, 1917. Serial No. 193,965.

To all whom it may concern:

Be it known that we, RAY P. PERRY and JOHN M. JACK, citizens of the United States, residing at Upper Montclair and Peoria, in 5 the counties of Essex and Peoria and States of New Jersey and Illinois, respectively, have invented certain new and useful Improvements in Processes of and Apparatus for Treating Felts and the like, of which 10 the following is a specification.

This invention relates to the manufacture of felts or papers adapted to be used in making so-called tarred or asphalt saturated felts especially felts of the character described and claimed in the co-pending application of R. P. Perry filed April 12, 1917, bearing Serial No. 161,670 and entitled "Felts and processes of making the same."

In the manufacture of felts of the character described in the above entitled application, difficulty is often experienced, especially when operating on a large or commercial scale due to the fact that the sheet of felt, containing as it does comminuted bituminous waterproofing material, preferably in filamentary form, scattered throughout the mass of the same and, therefore, present in substantial quantities at the surfaces of the sheet, when passing over the series of heated drying rolls, adheres to the rolls which gather particles of comminuted bituminous material from the sheet. This not only renders the sheet less perfect, but also interferes with the drying operation 30 since the adhering particles of bituminous material prevent the sheet passing over the drying rolls from coming into intimate contact with said rolls, and said particles also prevent the heat from being conducted as 35 efficiently to the sheet to be dried as would be the case if such particles did not adhere to the drying rolls.

The purpose of our invention is to provide a method and an apparatus whereby such undesirable adhesion of bituminous particles to the drying rolls of the usual paper-making machine is prevented in a manner that is at once simple and efficient, and does not necessitate any substantial alteration of the usual paper-making plant.

Referring to the drawing wherein we have diagrammatically illustrated a device embodying our invention and in which our process may be practised,

Figure 1 is an end elevation of a portion 55 of the drying mechanism with our invention applied thereto, and

Fig. 2 is a detailed view of a modification of our invention.

Referring to the species illustrated in Fig. 1, 10 indicates the sheet of felt containing comminuted fusible waterproofing material, preferably in filamentary form, as described in the co-pending application referred to above. This sheet passes in the usual manner over the series of cylindrical or other shaped heated driers 11, 11, 11. In order to prevent the undesirable adhesion of the particles of fusible waterproofing material present in the sheet to the surface of the driers 15 as referred to above, we interpose between the sheet and the heated surfaces of the driers a thin film of a liquid, preferably of an oily nature, such, for example, as any liquid lubricating oil, such as petroleum oil, coal tar oil, or oil tar oil. While this film may be interposed between the sheet and the driers by applying the same to the sheet, we prefer to apply this film to the driers since 20 we have found that in this way a more even 25 film is produced and that the operation of the process is more uniform where the film is applied to the heated surfaces of the driers. While various means may be employed 30 to effect the interposition of the film between 35 the sheet and the heated surfaces of the driers, we prefer to use the means illustrated. Such means comprise in the case of those 40 drying units the upper surface of which is 45 traversed by the sheet, supporting means 50 which support any suitably shaped receptacle 55 within which the lubricating or 60 similar oil 65 is contained. Dipping into the oil 65 within the receptacle 55 is the 70 porous member 75 of a wick-like nature. In 75 order to insure that the member 75 will be 80 constantly pressed with uniform pressure 85 against the bottoms of those drying rolls 11 to which the members 75 are applied, we 90 may interpose the coiled or other spring 95 members 75' between the member 75 and the bottom of the container 55 so that in this 100 way the members 75 will be pressed upwardly with uniform pressure against the 105 bottom surfaces of the corresponding drying members 11.

In order to apply the film of liquid to those of the drying members 11 whose bot-

tom surfaces are traversed by the sheet 10, we provide the supporting members 18 which support the receptacles or containers 17 within which is contained the oil or similar liquid 19 and into which dips the porous wick-like member 20 the bottom portion 21 of which comes in contact with the upper portions of the surfaces of the corresponding drying members 11.

10 The operation of the device is apparent from the above description. As the drying members 11 rotate in the directions indicated by the arrows, these members will rub against the porous wick-like members 14 and 21 which are kept continually moist by means of the oil within the receptacles 12 and 17, respectively. In this way there is interposed between the sheet 10 and driers 11 a thin film of oil which it is found substantially prevents any adhesion of the fusible waterproofing particles of the sheet 10 to the surfaces of the heated drying rolls. Where such particles, as may occasionally happen, are very loosely incorporated in the sheet 25 at the surface thereof, and, therefore, become separated from the sheet, while such particles may cling slightly to the surfaces of the heated drying rolls, this adhesion is very slight. In fact it is probable that the particle in a certain sense "floats" on the film of oil and its removal is a very easy matter. In order to effect the removal of such particles of fusible waterproofing material that may adhere to the rolls 11, we provide the scraping means or "doctors" preferably of a porous wick-like nature for the removal of surplus oil and the few particles that may adhere to the roll. These scraping devices consist in the case of those of the rolls whose under 40 surfaces are provided with the film of liquid of the members 15 located so as to clean off the surfaces of the drying rolls at a point immediately before the roll is to be given a new film of liquid. In the case of those of the drying units whose upper surfaces are provided with the film of oil or similar liquid, the cleansing means consist of the porous wick-like members 22 located in such a position with respect to the members 50 21 that the member 22 effects the removal of the surplus oil and of the few particles that may adhere to the driers 11 at a point immediately before the points at which the member 21 gives the driers 11 a new film of liquid.

In Fig. 2 we have illustrated a modification for providing the surfaces of the heated drying rolls with the film of liquid. In this modification we employ a pipe 30 provided with a series of equidistantly spaced perforations 31 of capillary size. Oil or a similar liquid 32 is forced under a given pressure from any suitable source of supply through the perforations 31 into the porous wick-like member 33 which completely surrounds

the pipe 30. This film producing device is so located with respect to the driers 11 that the said driers will be pressed against the members 33 at those portions of the surfaces of the driers which are not covered by the sheet 10.

By the above means, especially when we employ a liquid of an oily nature such as lubricating oil as, for example, petroleum oil, coal tar oil or oil tar oil, we are enabled to effectively dry a sheet of the nature described in the co-pending application referred to above without encountering any of the difficulties hitherto encountered in the manufacture of such a sheet on a commercial scale due to the adhesion to the surfaces of the heated driers of particles of fusible waterproofing material present in the sheet.

What we claim is:

1. In the process of drying, by the application of heated surfaces, felts for roofing and the like having on at least one side thereof a substantial amount of fusible adherent waterproofing material in comminuted form, the step of interposing a film of liquid between the sheet and the surfaces to prevent the adhesion of said sheet or any portions of the same to the said heated surfaces.

2. In the process of drying, by the application of heated surfaces, felts for roofing and the like having on at least one side thereof a substantial amount of fusible adherent waterproofing material in filamentary form, the step of interposing an oily liquid between the sheet and the surfaces to prevent the adhesion of said sheet or any portions of the same to the said heated surfaces.

3. In the process of drying, by the application of heated surfaces, felts for roofing and the like having on at least one side thereof a substantial amount of fusible adherent waterproofing material in comminuted form, the step of applying a film of liquid to the said surfaces to prevent the adhesion of said sheet or any portions of the same to the said surface.

4. In the process of drying, by the application of heated surfaces, felt for roofing and the like having on at least one side thereof a substantial amount of fusible adherent waterproofing material in comminuted form, the step of applying an oily liquid to the said surfaces to prevent the adhesion of said sheet or any portions of the same to the said surface.

5. The process of drying a sheet of felt having particles of fusible bituminous material distributed therein, which comprises the steps of passing the sheet over a heated, moving, cylindrical surface at substantially the same speed as said surface moves, and simultaneously interposing a film of oily liquid between said sheet and said surface.

6. In a paper-making machine a plurality

of heated drying surfaces, and means for supplying a liquid between the said heated drying surfaces and the paper passing over the same to be dried.

5. 7. In a paper-making machine, a plurality of heated drying surfaces, and means for supplying substantially all of the said heated drying surfaces with films of an oily liquid, whereby such films will be interposed between the said surfaces and the material 10 passing over the same to be dried.

8. In a paper-making machine, a plurality of heated drying surfaces, means for supply-

ing substantially all of the said heated drying surfaces with films of lubricating oil, 15 whereby such films will be interposed between the said surfaces and the material passing over said surfaces to be dried, and means for removing any surplus oil and such portions, if any, of the material as may 20 adhere to the said surfaces.

In testimony whereof we affix our signatures.

RAY P. PERRY.
JOHN M. JACK.
